UNITED STATES PATENT OFFICE.

JULIUS KRUTTSCHNITT, OF NEW CANAAN, CONNECTICUT, AND EDWIN H. BELL, OF CHICAGO, ILLINOIS; E. MINNA KRUTTSCHNITT EXECUTRIX OF SAID JULIUS KRUTTSCHNITT, DECEASED.

TIE PLATE.

Application filed June 1, 1925. Serial No. 34,028.

To all whom it may concern:

Be it known that we, JULIUS KRUTTSCHNITT and EDWIN H. BELL, citizens of the United States, residing, respectively, in the town of New Canaan, of the county of Fairfield, State of Connecticut, and in the city of Chicago, county of Cook, State of Illinois, have invented certain new and useful Improvements in Tie Plates, of which the following is a specification, reference being had to the accompanying drawings, and to the reference characters marked thereon, which form a part of this specification.

This invention relates to tie plates, and more particularly to plates of channel form, i. e. having tie-embracing side flanges.

Many plates suitable as to form, section or weight to one location in track will not give satisfactory service in another location where different conditions exist. In sandy country, for example, extreme atmospheric conditions affect the tie and shorten its life. The tie is affected with a species of dry rot, the fibres separate, it splits longitudinally, and disintegration occurs. In such situations, the spikes loosen and fail to hold the plate to the tie, and the gauge of the rails cannot be maintained, requiring constant regauging and replacements.

This destructive atmospheric action upon the ties is greatly increased when the tie plates used are of a section and weight desirable for use in track in mountainous country having sharp curves and high grades. The "wave motion" of the rails produces a hammering action of the plate on the tie and the heavier the plate, the greater the blow.

It is the primary object of the present invention to produce a tie plate adapted for all atmospheric and topographical conditions in track and especially to meet and overcome the difficulties above mentioned.

To the accomplishment of these and other objects, our invention consists in the devices and combinations of devices herein illustrated, described and more particularly pointed out in the appended claims.

In the drawings:

Figure 1 is a top plan view of one form of tie plate embodying our invention, shown upon a tie.

Figure 2 is a side view of the same.

Figure 3 is an end view of the same, the tie being in section, taken in the vertical plane indicated by the dotted line 3-3 on Fig. 2.

Figure 4 is a central, longitudinal, sectional view of the same, the section being taken in the vertical plane indicated by the dotted line 4-4 on Figure 1.

Figure 5 is a bottom plan view of the tie plate.

Figure 6 is a transverse, sectional view of the plate, the section being taken in the vertical plane indicated by the dotted line 6-6 on Figure 2.

Figures 7 and 8 are views similar to that of Figure 6, but showing two modified forms of plate.

Figure 9 is a bottom plan view of another modification.

Figure 10 is a transverse, sectional view of this modification, the section being in the vertical plane indicated by the dotted line 10-10 on Fig. 9.

Figure 11 is a bottom plan view of another modification.

Figure 12 is a transverse, sectional view of this modification, the section being in the vertical plane indicated by the dotted line 12-12 on Figure 11.

Figure 13 is a bottom plan view of a further modification, and

Figures 14 and 15 are sectional views of this modification, the sections being taken in the vertical planes indicated by the dotted line 14-14 on Figure 13 and the dotted line 15-15 on Figure 14, respectively.

In said drawings, in Figures 1 to 6, inclusive, our preferred form of tie plate is shown, positioned upon a tie B, ready to be but not actually seated or imbedded thereon. The plate A is provided upon its top surface with a transverse rib or rail abutting shoulder 1, preferably extending higher above the plate at its central portion 2 than at its two ends 3, 3. The rail bearing surface of the plate is canted, that is to say, it inclines from the base of the shoulder 1 towards but not entirely to the inner end 5 of the plate, the inclination being indicated by the line 4. The rail bearing surface is also convexly rounded or curved from one side margin to the other, to produce a crowned or cambered top, as indicated by the convex line 6. The canted and cambered rail bear-

ing surface is unbroken, but manifestly may be provided with grooves or recesses familiar in other types of plate, if desired.

At each side margin, the plate is provided with a downwardly projecting, tie embracing flange 7, running longitudinally of the plate, i. e. in the direction of the tie B, and transverse to the direction of the rail.

The bottom of the plate is thus of general channel form, the two parallel side flanges 7, 7, being spaced apart sufficiently to embrace or lie over the upper portion of the side surfaces of the tie B.

The tie bearing surface of the bottom of the plate, intermediate the flanges 7, may be of various configurations. As shown in Figs. 1 to 6, inclusive, the bottom is provided with a median, undulated section, indicated as a whole by the letter C, and extending from the outer to the inner end of the plate. This section C is formed by a plurality of parallel, arcuate undulations, grooves or depressions 8, the long dimension of each groove being transversely of the plate and at right angles to the longitudinal side flange 7. These arcuate surfaces 8 intersect to form a plurality of parallel, short, intermediate ribs 9 which also extend transversely of the plate. These undulations 8 and ribs 9, in this form of plate, do not extend to the flanges 7 at the sides of the plate, thereby forming, intermediate their ends and said side flanges 7, relatively narrow, flat, tie bearing surfaces 10, 10, which extend longitudinally of the plate and parallel to the flanges 7. Spike holes 11 may be placed, as shown, or otherwise, as desired. The flanges 7 are preferably somewhat tapered, the inner surfaces 12 inclining slightly outwardly and downwardly, thereby cooperating with the other features of the bottom to compress the fibres of the tie and hold the plate A more firmly to the tie B.

The plate A is initially positioned upon the tie as shown in Figures 1 to 6, inclusive. When pressure is brought upon it by the passing of train loads over it, or otherwise, the relatively narrow surfaces 10, 10, will bear into and make seats below the normal top surface of the tie. The ribs 9 will also enter the tie lengthwise of the grain of the wood, spreading the fibres apart. When the plate is firmly seated, it will be found that the fibres of the tie have been compressed and that the originally flat surface of the tie has become changed into a configuration complementary to the under surface of the bottom of the plate. It will also be found, after a comparatively short period of use in track, that this complementary tie surface has become considerably hardened and the tie compacted, so to speak, whereby the tendency to disintegrate is reduced and the life of the tie prolonged.

The normal function of a camber or crown on the rail bearing surface to counteract the

tendency of plates to move or shift and to cause "rattle" due to the wave motion of the rails, is raised to a maximum, when the plate is provided with the downwardly projecting, tie embracing side flanges 7, 7, the crown and the flanges thus cooperating with each other and with the spikes to hold the plate A firmly upon the tie B.

By making the rail abutting rib 1 of unequal height, we are enabled to save metal, which is a consideration when plates are sold by weight, and at the same time retain a high shoulder across the median longitudinal line of the cambered rail bearing surface of sufficient strength and size to withstand the side thrusts and strains from passing trains, while the parts 3, 3 of the shoulder are sufficiently high and strong for this purpose. The rib 1, though of unequal heights, is of such length as to cooperate with the side flanges 7 to prevent the tendency of the plate A to twist or shift angularly on the tie B.

In the plate above described, the tie bearing surfaces 10 and the points of the ribs 9 are in the same horizontal plane, as will be seen by reference to Fig. 4.

In the modification shown in Figure 7, the bottom, as a whole, is concaved or curved substantially parallel to the curvature of the crowned top. The body of the plate, therefore, will be of even cross-sectional area throughout its width, instead of being thicker at the center than at its sides, as is the plate illustrated in Figs. 1 to 6. In all other respects, the plate shown in Figure 7 corresponds with the plate shown in Figs. 1 to 6.

The bottom of the plate intermediate the flanges 7, 7, may be of various configurations, and in the modification shown in Figure 8, the grooves 8 are omitted and the tie bearing surface 13 is continuous. It is shown as concavely curved corresponding with the convex curvature of the crowned top and of even thickness, as is the modification shown in Fig. 7. In all respects other than by the omission of the grooves 8, it corresponds to the plate shown in Figure 7.

In the modification illustrated in Figures 9 and 10, the plate is in all respects like that first described with the exception that the grooves or recesses 8 and their dividing ribs 9 extend from one side flange 7 to the other side flange 7, thereby omitting the flat tie bearing surfaces 10, 10.

In the modification shown in Figures 11 and 12, the plate is in all respects like the plate shown in Figures 1 to 6, inc., with the exception that the grooves or recesses 8 and their intervening ribs 9, while parallel to each other, extend lengthwise of the plate at a different angle to the side margins of the surfaces 10; that is, diagonally instead of at right angles thereto.

In the modified form shown in Figures 13, 14 and 15, the space between the inner faces of the side flanges 7 is provided with a pair of flat surfaces 14, 14, one at each end of the plate, and with an intermediate recessed or grooved section C^a. The grooves 15 and intervening ribs 16 (corresponding with grooves 8 and ribs 9 before described) while parallel to each other, are also parallel to the side flanges 7.

In all of the plates, it will be seen that considerable metal may be saved, to lighten the weight, by tapering the top surface downwardly from behind the shoulder rib 1 towards the outer end of the plate, as shown at 17, and similarly, tapering the other surface, from where the cant and camber leave off, downwardly toward the inner end 5 of the plate, as shown at 18.

20 The plate in all of the forms shown, and in other modifications which will be obvious to railway engineers familiar with track construction and conditions, is strong, durable and adapted to meet all the various 25 requirements of road conditions.

We claim as our invention:

1. A tie plate having on its bottom a flange depending from each side margin and extending lengthwise of the plate and having 30 a configurated space lying above the plane of the bottom and intermediate said side flanges, the plate having on its top a transversely located rail abutting shoulder and a rail bearing surface, the rail bearing 35 surface being canted from the shoulder to the end of the plate and being crowned transversely of the plate.

2. A tie plate having tie embracing, side flanges depending from its bottom and extending lengthwise of the plate, the bottom 40 of the tie plate adjacent said flanges being flat, and a configurated surface intermediate said spaced-apart flat portions and extending above the horizontal plane thereof.

45 3. A tie plate having tie embracing, side flanges depending from its bottom and extending lengthwise of the plate, spaced apart flat bearing surfaces adjacent said flanges, a configurated tie bearing surface intermediate said spaced apart flat surfaces, said plate having on its top a rail abutting shoulder and a canted and crowned rail bearing surface.

50 4. A tie plate having on its top a transversely located, rail abutting shoulder and a canted and crowned rail bearing surface, and tie-embracing, side flanges depending from its bottom and extending lengthwise of the plate, and a plurality of arcuate recesses or grooves, and dividing ribs, intermediate of and angularly disposed with reference to said side flanges.

55 5. A tie plate having on its top a transversely located, rail abutting shoulder of variable height throughout its length and a

canted and crowned rail bearing surface, and having tie embracing, side flanges depending from its bottom and extending lengthwise of the plate.

6. A tie plate having on its top a transversely located, rail abutting shoulder of greater height along its central portion than at its ends, and a rail bearing surface convexly curved transversely from side to side and canted from the shoulder toward the inner end of the plate, and a flange depending from each side margin of its bottom and extending lengthwise of the plate.

7. A tie plate having on its bottom tie embracing, depending side flanges extending lengthwise of the plate, the bottom of the plate intermediate the side flanges having a plurality of transversely extending undulations and a flat tie bearing surface between said undulations and said flanges, 85 said plate having on its top a transversely located rail abutting shoulder and a canted and crowned rail bearing surface.

8. A tie plate having on its bottom tie embracing, side depending flanges extending lengthwise of the plate, two relatively narrow, spaced apart, tie bearing surfaces extending from end to end of the plate, parallel with said flanges, a plurality of parallel grooves or recesses extending transversely of the plate between said surfaces, and tie engaging ribs between said grooves, said plate having on its top a transversely extending rail abutting shoulder, higher at its central portion than at its ends, and a rail bearing surface convexly curved transversely from side margin to side margin, and also canted from said shoulder toward the inner end.

9. A tie plate having on its bottom tie 105 embracing, side depending flanges extending lengthwise of the plate, two relatively narrow, spaced apart, tie bearing surfaces extending from end to end of the plate, parallel with said flanges, a plurality of parallel grooves or recesses extending transversely of the plate between said surfaces, and tie engaging ribs between said grooves, said plate having on its top a transversely extending rail abutting shoulder, higher at 110 its central portion than at its ends, and a rail bearing surface convexly curved transversely from side margin to side margin, also canted from said shoulder toward the inner end, the top of the plate being inclined upwardly and inwardly from each end, and the inner surfaces of each depending side flange flaring slightly downwardly and outwardly.

In testimony, that we claim the foregoing 125 as our invention, we hereunto affix our signatures.

JULIUS KRUTTSCHNITT.
EDWIN H. BELL.
